(57) **CLAIM**

The ornamental design for a multi-terrain landing gear for unmanned aircraft, as shown and described.

DESCRIPTION

FIG. 1 is a perspective view showing a first embodiment of a multi-terrain landing gear for unmanned aircraft;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing multi-terrain landing gear for unmanned aircraft in an alternate environment of use attached to an unmanned aircraft;

FIG. 9 is a perspective view showing second embodiment of a multi-terrain landing gear for unmanned aircraft;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a perspective view showing multi-terrain landing gear for unmanned aircraft in an alternate environment of use attached to an unmanned aircraft;

FIG. 17 is a perspective view showing a third embodiment of a multi-terrain landing gear for unmanned aircraft;

FIG. 18 is a front view thereof;

FIG. 19 is a rear view thereof;

FIG. 20 is a left side view thereof;

FIG. 21 is a right side view thereof;

FIG. 22 is a top view thereof;

FIG. 23 is a bottom view thereof;

FIG. 24 is a perspective view showing the multi-terrain landing gear for unmanned aircraft in an alternate environment of use attached to an unmanned aircraft;

FIG. 25 is a perspective view showing a fourth embodiment of a multi-terrain landing gear for unmanned aircraft;

FIG. 26 is a front view thereof;

FIG. 27 is a rear view thereof;

FIG. 28 is a left side view thereof;

(Continued)

FIG. 29 is a right side view thereof;

FIG. 30 is a top view thereof;

FIG. 31 is a bottom view thereof; and,

FIG. 32 is a perspective view showing the multi-terrain landing gear for unmanned aircraft in an alternate environment of use attached to an unmanned aircraft.

In the drawings, the broken lines depict environmental subject matter only and form no part of the claimed design.
